UNITED STATES PATENT OFFICE

GILBERT CLARKE, OF GATOOMA, SOUTHERN RHODESIA, SOUTH AFRICA

MOSQUITO NET FOR BEDSTEADS

Application filed February 14, 1930. Serial No. 428,448.

This invention relates to a new or improved mosquito net adapted to bedsteads and has for its object to provide a folding cover in the nature of a Cape cart hood which is covered with mosquito netting.

In a convenient embodiment of my present invention I provide for a hood the frame of which is made of any suitable material such as wood or any light metal, the hood being of such size so as to cover the whole or part of the bed as desired when fully opened.

The hood consists mainly of two upright beams or rods rigidly attached to the head bedpost of a bedstead, and two main beams or rods hinged at convenient points to the upright members, these beams being connected by transverse members. The whole of the device is covered with mosquito netting. When the hood is completely unfolded the two main beams do not rest on the bed but maintain a position at a slight angle to the horizontal, due to the netting, which is attached thereto. Part of the netting hangs freely over the beams onto the bed, this constituting a fringe to which beads or the like ornaments may be attached for the purpose of keeping the fringe down on to the bed.

A further object of my invention is to provide for means whereby the hood can be closed, opened, or left in any desired intermediate position. In a suitable embodiment of my invention I accomplish this object by making use of a window blind roller attached to the upright members, which operates the invention by suitable cords. In another form use may be made of spring washers fitted to the hinge or pivot points of the main beams, or balance weights may be employed to operate the opening and closing of the cover. In another embodiment my invention could be operated by electricity thereby adding to the convenience of the device. The sizes and natures of these appliances should be such that the bedstead could easily be removed or transferred without the necessity of dismantling.

In order that my invention may be readily understood and carried into practice reference is hereby made to the accompanying drawings which show one embodiment of my

invention in which a blind roller is used to operate the hood. In the drawings:

Figure 1 is a side elevation of the bedstead fitted with my invention.

Figure 2 is a plan view on Figure 1.

Figure 3 is a perspective view of the same.

Figure 4 is a detail transverse sectional view of the spring roller on a somewhat larger scale than the other figures.

It will be observed that in all the views the cover is in its open position whereby the bed is covered with the netting.

Referring to these drawings wherein like reference numbers indicate the same parts wherever occurring throughout all the views 1 denotes the head bedpost of the bedstead to which are attached the upright members 2 of the folding cover.

The main members designated 3 are hinged at 4 to members 2, and 5 indicates the window blind roller attached horizontally to the members 2. The cord 6 passing round roller 5 a few times is attached to the transverse member 7 fixed to beams 3, and has a free end 8 hanging down within easy reach of the occupant of the bed. To raise the hood it is necessary to give the string 8 a pull and then to release it in the same way a window blind is released, thus enabling the roller 5 to rewind cord 6 and in this way raising the beams 3 to a vertical position. It will be evident that the hood could either be operated from the inside or outside as desired.

In the present case illustrated I also provide for a cord 9 which is wound separately on roller 5, this cord passing over the top fixed member 10 to the end cross member 11 of beams 3 serving the purpose to prevent the netting 12 fouling with the roller 5, and to keep the netting from sagging.

The improvements herein set forth are not limited to the precise construction as described or as illustrated but may be embodied in various forms and modifications without departing from the spirit and scope of the invention.

What I claim is:

1. A mosquito bar comprising in combination a bedstead having head bedposts, a pair of upright bars secured to the bedposts, a

100

- spring roller connecting said upright bars, a member connecting the upper ends of said upright bars, a pair of side bars having their inner ends pivotally connected to the upright bars, cross bars connecting said side bars at spaced points at the outer ends of said side bars, a cord attached to said spring roller and to one of the said cross bars and a net arranged over the head of the bedstead
5 and over the said member which connects the upper ends of said upright bars and over the outer free end and outer sides of said side bars and having portions depending from said side bars and their outer connecting cross bar.
10 2. A mosquito bar as claimed in claim 1, including also a cord arranged under the net and connecting the outer cross bar of the side bars and the member of the upright bars
15 and serving to prevent the net from coming in contact with the hoisting cord and the spring roller.

Signed at Durban, Province of Natal, South Africa, this 7th day of January, A. D.

25 1930.

G. CLARKE.
